J. S. JAMMER

REPEATER CIRCUITS

Filed Oct. 29, 1920

Fig. 2.

Inventor:
Jacob S. Jammer

by W. Beatty Atty.

UNITED STATES PATENT OFFICE.

JACOB S. JAMMER, OF NEW YORK, N. Y., ASSIGNOR TO WESTERN ELECTRIC COMPANY,
INCORPORATED, OF NEW YORK, N. Y., A CORPORATION OF NEW YORK.

REPEATER CIRCUITS.

Application filed October 29, 1920. Serial No. 420,478.

To all whom it may concern:

Be it known that I, JACOB S. JAMMER, a citizen of the United States, residing at New York, in the county of New York and

5 State of New York, have invented certain new and useful Improvements in Repeater Circuits, of which the following is a full, clear, concise, and exact description.

This invention relates to two-way repeating systems particularly of the type in which 10 a plurality of repeaters are employed between each set of connected line sections.

Heretofore in two-way repeating systems employing two repeater elements, it has been 15 common practice to employ one of the repeaters for repeating in one direction between the line sections, the other repeater being employed for repeating in the opposite direction.

20 In accordance with this invention it is possible to employ both of the repeaters for repeating in either direction whereby the power output of the repeater unit is doubled, so that a more efficient use of the repeater 25 unit results therefrom.

The preferred form of this invention employs a repeater unit, in which two repeaters are connected in opposition, an arrangement known in the art as a push-pull circuit. In 30 such an arrangement, certain portions of the input and output circuits of the repeaters are individual, while other portions are in common. In such a push-pull arrangement, currents may be applied to the common portion 35 of the input circuit and led off from the common portion of the output circuit without interfering in any wise with currents applied to the individual portions of the input circuit and led off from the individual 40 portions of the output circuit. The push-pull arrangement, therefore, may be employed for two-way repeating by having input and output connections for repeating in one direction applied to the common portions of the input and output circuits and by having the corresponding connections for repeating in the other direction applied to the individual portions of the input and output circuits.

45 This invention will be better understood by reference to the following detailed description taken in connection with the accompanying drawing, in which Fig. 1 illustrates this invention embodied in a 22 type repeater circuit and Fig. 2 illustrates this

invention in connection with a four-wire repeater circuit.

Referring to Fig. 1, the electric system disclosed therein comprises two line sections 5 and 6 which terminate respectively in balancing artificial lines 7 and 8. Included between line section 5 and artificial line 7, are two windings 9 and 10 of a three-winding transformer. Included similarly between line section 6 and artificial line 8, 60 are the windings 11 and 12 of a second three-winding transformer.

Connected between the two three-winding transformers, is a two-way repeater comprising similar vacuum tube repeater elements 15 and 16, which are arranged in the so-called push-pull circuit, repeaters 15 and 16 being of the three-electrode type now well-known in the art. The individual portions of the input circuits of repeaters 15 75 and 16 are associated with the third winding 19 of the three-limb transformer 20 by means of the transformers 21 and 22. The common portion of the input circuit of repeaters 15 and 16 is associated with the 80 third-winding 24 of the three-winding transformer 25 by means of transformer 26.

The individual portions of the output circuits of the two repeaters are connected to the midpoints of transformer windings 11 and 12 by means of the two transformers 27 and 28. The common branch of the output circuits of the repeaters by transformers 29, is connected to the midpoints of transformer windings 9 and 10. Tubes 15 and 16 should preferably have similar characteristics so that their output circuits are the same for given changes in grid potential. Input transformers 21 and 22 should be so designed that the incoming currents from line section 5 impress equal and opposite potentials on the two-control electrodes 31 and 32 of the repeaters. The currents in the secondary winding of transformer 26 in such a case, due to currents from line 5, would 90 be zero. Another way of stating this relationship is, that currents from line section 6 through transformer winding 24 and transformer 26 should impress equal and opposite currents in these winding on transformers 21 and 22 which are in circuit with winding 19. With respect to the output transformers 27, 28 and 29, transformers 27 and 28 should be so designed that amplified 95 currents in the output circuits of repeaters 110

15 and 16 due to currents impressed by input transformers 21 and 22, produce zero current in the secondary winding of output transformer 29, or, in other words, amplified currents in the output circuits of the repeaters due to currents impressed by the input transformer 26 should produce equal and opposite currents in the secondary windings of transformers 27 and 28.

10 The method of operation of the arrangement of Fig. 1, may now be described as follows:

Incoming currents from line section 5 are impressed through windings 10 and 19 of transformer 20 and transformers 21 and 22 upon the two control electrodes of the repeaters in such a manner that the potentials of the two electrodes are changed in equal and opposite amounts. Corresponding amplified currents are produced in the same direction in transformers 27 and 28 so that amplified currents are impressed thereby upon the outgoing line section 6. Since the currents flowing in the primary windings of transformers 27 and 28, are in the same direction, it follows that none of the amplified currents are fed back to line 5 through the transformer 29 which is located in the common portions of the output circuit. Since connections from the secondary windings of transformers 27 and 28 are made to the mid-points of transformer windings 11 and 12, none of the amplified currents can find their way back through the third-winding 24 of transformer 25, into the input circuit of the repeater.

Incoming currents from line section 6, flowing serially through both sections of windings 11 and 12, by means of the third winding 24 are impressed upon the common portion of the input circuit of the repeater whereby the currents to be amplified, produce equal variations of the same polarity in the potential of the two control electrodes 31 and 32. Currents so impressed upon the two control electrodes will produce amplified currents in opposite directions in the primary windings of transformers 27 and 28, but will produce additive amplified currents in the primary winding of transformer 29. It follows therefore that the amplified currents, by means of transformer 29, will be impressed upon the outgoing line section 5.

55 From the above description, it is apparent that repeaters 15 and 16 are employed for amplifying currents in both directions between the line sections 5 and 6.

It is obvious that transformers 21 and 22 may be combined into one transformer on a single core structure as shown by transformer 41 of Fig. 2; a similar substitution can be made for transformers 27 and 28.

Fig. 2 illustrates this invention in connection with a four-wire repeater circuit, and

the operation of the system is essentially the same as that described in connection with Fig. 1. Incoming currents from line section 40, by means of transformer 41, impress equal and opposite potentials upon the two control electrodes of the repeaters 42 and 43. The amplified currents in the output circuit produced thereby, flow in the same direction from the two halves of the primary winding of transformer 44 so that the amplified currents are impressed upon the outgoing line section 45. Incoming currents from line section 46, by transformer 47, are impressed upon the common portion of the input circuit of the two repeaters and consequently produce additive amplified currents in the primary winding of transformer 48 so that these amplified currents may be impressed upon the outgoing line section 49.

Vacuum tube repeaters 52 and 53 are associated in a similar manner with line sections 54, 55, 56 and 57 for repeating currents from line section 56 to line section 57 and from line section 55 to line section 54.

In case a repeater is desired for phantom circuit operation of the two four-wire repeater circuits shown in Fig. 2, vacuum tube repeaters 60 and 61 may be provided, having an input transformer 62 for line sections 40 and 49 connected to the mid points of transformers 41 and 48. Outgoing transformer 64 for the two line sections 45 and 46 may be connected to mid points of the windings of transformers 44 and 47. In a similar manner, an input transformer 63 may be provided for line sections 55 and 57 having its primary winding connected to the mid points of windings of transformers 67 and 68. Outgoing transformer 70 for the derived phantom circuit of line sections 54 and 56, may have its secondary winding connected to the mid points of windings of transformers 71 and 72. Repeaters 60 and 61 will, therefore, impress upon the phantom circuit of sections 45 and 46, amplified phantom current from sections 40 and 49 and will also impress upon the phantom circuit of line sections 54 and 56 phantom current from line sections 55 and 57.

Although this invention has been described in connection with repeaters of the three-electrode type, it is to be understood that repeaters of other types may be employed without departing, in any wise, from the spirit of this invention. It is also to be understood that this invention is not limited to 22 repeater circuits or four-wire repeater circuits, but may be employed in any type of repeating system in which it is desired to repeat more than one set of signals.

What is claimed is:

1. In an electric system, a plurality of repeaters, having input and output circuits, said input circuits having portions in com-

- mon and other portions individual to each repeater, means for impressing signals upon the common portion of said input circuits, means for impressing other signals upon the individual portions of said input circuits, and connections for selectively leading-off in different electrical paths said first mentioned and said second mentioned signals from said output circuits.
10. 2. In combination, two line sections, two vacuum tubes having input and output circuits, said input circuits having portions in common and other portions individual to each tube, means for impressing signals upon the common portion of said input circuits, means for impressing other signals upon the individual portion of said input circuits, an impedance coupling between one of said line sections and said output circuits for impressing said first mentioned signals upon said one line section, and an impedance coupling between said output circuits and the other of said line sections for impressing thereon said second mentioned signals.
25. 3. In combination, a plurality of vacuum tubes each having a control electrode and an output circuit, means for impressing signals upon said control electrode whereby the potential of one of said electrodes at one instant is changed differently from the potential of another of said electrodes, means for impressing upon said control electrodes other signals whereby the potentials of said electrodes are changed similarly, and connections from said output circuits for selectively leading-off said first mentioned and said second mentioned signals.
40. 4. In combination, two vacuum tubes each having a control electrode, a cathode, an anode, and an output circuit, means for impressing signaling currents upon said control electrodes whereby their potentials are changed oppositely, means for impressing other signaling currents upon said control electrodes whereby their potentials are changed similarly, and connections to said output circuit individually leading-off one set of said signals.
45. 5. In combination, a line, a plurality of repeaters having input and output circuits, portions of said input and output circuits being individual to each repeater, portions of said input and output circuits being common to said repeaters, means for impressing signals from said line upon said common input circuit portions, and means for impressing on said line currents from said individual portions of said output circuit.
6. In combination, a line, a plurality of repeaters having input and output circuits, portions of said input and output circuits being individual to each repeater, portions of said input and output circuits being common to said repeaters, means for impressing signals from said line upon said individual portions of said input circuits, and means for impressing currents upon said line from the common portion of said output circuits.
7. In an electric system, two line sections, two vacuum tube repeaters located therebetween, and connections for utilizing said repeaters in opposition for repeating in one direction between said lines and for utilizing said repeaters in parallel for repeating in the opposite direction.
8. In an electric system, two line sections, and a two-way repeating system therebetween comprising two vacuum tube repeaters each having input and output circuits, said input circuits having portions in common and other portions individual to each repeater, said output circuits having portions in common and other portions individual to each repeater, means for impressing upon the individual portions of said input circuits currents from one of said line sections, means for impressing on the other line section currents from the individual portions of said output circuits while preventing the currents so impressed from being fed back upon the input circuits of said repeaters, means for impressing upon the common portion of said input circuits currents from said other line section, and means for impressing on said one line section currents from the common portion of said output circuits while preventing currents so impressed from being fed back upon the input circuits of said repeaters.

In witness whereof I hereunto subscribe my name this 25th day of October, A. D. 1920.

JACOB S. JAMMER
